NO. 15,642

DEC 23, 1884

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,642, dated December 23, 1884.

Application filed November 15, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,512;) and I do hereby declare that the engraved prints accompanying this specification convey to any one accustomed to using paper patterns a clear understanding of how a garment made up by the pattern will appear.

The design shows a round walking-skirt and a basque. The skirt exhibits a deep plain panel at the right side; a deep front drapery rounding away from the panel, falling in a deep point at the left side of the skirt and displaying draping plaits in its left back edge; a scarf-drapery that appears to cross the upper part of the front drapery diagonally and displays gatherings in its front and back edges; a deep square back drapery that displays draping plaits high up in its front edges and

loopings high up at the center. The basque exhibits narrow pointed center fronts, deeper closely-fitted side fronts that shape a point at 25 each side of the center fronts and arch high over the hips, the center fronts being crossed by pointed straps that appear to be extensions of the right-side front, a deep closely-fitted back that displays under-folded plaits 30 at the lower end of its middle seam, and under-folded plaits and a forward-turning revers below the waist-line at each side back seam, coat-sleeves, and a standing collar.

What I claim as my invention, and desire to 35 secure by Letters Patent, is—

The design for a lady's costume, as shown in the engraved prints accompanying this specification.

SARAH JANE SHIELS.
